DESIGN FOR A PROJECTION PRINTER

Theodore G. Clement, Rochester, N. Y., assignor
to Eastman Kodak Company, Rochester, N. Y.,
a corporation of New Jersey

Application February 18, 1941, Serial No. 99,065

Term of patent 7 years

To all whom it may concern:

Be it known that I, Theodore G. Clement, a citizen of the United States, residing in Rochester, in the county of Monroe and State of New York, have invented a new, original, and ornamental Design for a Projection Printer, of which the following is a specification, reference being had to the accompanying drawings, forming a part thereof.

In the drawings:

Fig. 1 is a front and side perspective view of the projection printer showing my new design.

Fig. 2 is a back and side perspective view of the projection printer shown in Fig. 1.

I claim:

The ornamental design for a projection printer, as shown.

THEODORE G. CLEMENT.
